CASSEROLE COVER

Glenn B. Beckman, Corning, N.Y., assignor to Corning Glass Works, Corning, N.Y.

Filed Mar. 1, 1972, Ser. No. 231,058

Term of patent 14 years

Int. Cl. D7—02

U.S. Cl. D7—40

Fig. 1

Fig. 2

Fig. 3

Fig. 4

Fig. 5

FIG. 1 is a top plan view of a casserole cover embodying my new design.

FIG. 2 is an elevational view partially in section.

FIG. 3 is a bottom plan view.

FIG. 4 is an enlarged fragmental view in elevation taken along line 4—4 of FIG. 3.

FIG. 5 is an enlarged fragmental view in elevation taken along line 5—5 of FIG. 3.

I claim:

The ornamental design for a casserole cover, as shown.
